US0D1063259S

(12) **United States Design Patent** (10) **Patent No.:** **US D1,063,259 S**
(45) **Date of Patent:** **** Feb. 18, 2025**

(54) **REMOTE CONTROLLED PET TRAINING DEVICE**

(71) Applicant: **Shenzhen kersonic Intelligent Technology Co., Ltd.**, Guangdong (CN)

(72) Inventor: **Yongkai Zhou**, Guangdong (CN)

(73) Assignee: **Shenzhen kersonic Intelligent Technology Co., Ltd.**, Shenzhen (CN)

(**) Term: **15 Years**

(21) Appl. No.: **29/863,548**

(22) Filed: **Dec. 20, 2022**

(51) **LOC (15) Cl.** **30-99**

(52) **U.S. Cl.**

USPC **D30/199**

(58) **Field of Classification Search**

USPC D10/78, 80, 104.1; D13/168, 154; D14/137, 217, 218; D30/144, 151, 152, D30/160, 199

CLAIM

The ornamental design for a remote controlled pet training device, as shown and described.

DESCRIPTION

FIG. 1 is a perspective view of a remote controlled pet training device design showing my new design.

FIG. 2 is a front view of a remote controlled pet training device.

FIG. 3 is a rear view of a remote controlled pet training device.

FIG. 4 is a left side view of a remote controlled pet training device.

FIG. 5 is a right side view of a remote controlled pet training device.

FIG. 6 is a top view of a remote controlled pet training device; and,

FIG. 7 is a bottom view of a remote controlled pet training device.

1 Claim, 7 Drawing Sheets
